CORNER BLOCKING PLATE

William W. Lemen and Abner P. Offutt,
Glendale, Calif.

Application February 18, 1941, Serial No. 379,476

1 Claim. (Cl. 20—76)

The principal object of our invention is the provision of a device adaptable for instantaneous attachment, for example, to the respective corners of a room, staircase, or the like, and right angular formations of any sort, whether embraced in the lower portion of a room structure adjacent the floor, or at the upper portion thereof adjacent the ceiling, and kindred other places where it is desired to change any right angular formation into a smoothly finished rounded one.

The paramount objective of the present invention is to provide an unmistakable and highly distinguishing improvement over similar devices of said character, the Jackson device, Patent No. 1,830,108, issued November 3, 1931, and the MacDonald device, Patent No. 1,622,656, issued March 29, 1927, in particular, ownership whereof is now possessed by the herein applicants, and recorded by assignment duly made in the United States Patent Office, applicant's improved corner blocking plate being absolutely devoid of the plane surface the MacDonald corner plate provides and which at best, although covering the sharp right angular corner of the walls of a room adjacent the floor, for example, in turn creates two oblique angles, to all intents and purposes as fully objectionable as the right angular corner eliminated thereby; the Jackson device, on the other hand, furnishes a corner block conforming in its contour with the base shoe and base shoe moulding in manner equally as objectionable, since its formation creates a so-called dust collecting pocket, moreover, it presents no such graceful sweeping covering as applicant's device herein disclosed.

It is thus a highly important object of the present invention to provide a device completely eliminating the defects and undesirable features of each of said patents, and, at the same time, improved as to general appearance, said latter feature in its physical aspects, being the more fully appreciated when viewed in a room of a pretentious furnished mansion and higher class homes where round cornered rooms predominate over the squared cornered rooms.

A further object of the herein invention is to provide a device eliminating all necessity for providing a mitered or other close-fitting joint of the base shoe moulding, a gap of an inch or more in the jointure being readily covered, and thus making possible both a saving in time and material over present practice where no such corner blocking plate is employed.

A further important object of the present invention is the provision of a device providing a

snugly fitting corner covering arranged either to overlap or extend flush with the base shoe moulding, as may be desired, and so positioned, leaving no recessed or protruding portions.

5 And a further object is to provide a device of
said character, which, though having an inclina-
tion from the perpendicular sufficient to extend
over and snugly contact the base shoe mould-
ing, is so shaped from the apex of the plate to
10 its edge touching the floor, for example, as to
provide but little, if any, surface for the accu-
mulation of dust upon the plate proper. There
is thus provided an ingenious device formed to
snugly overlap the moulding to which it is suit-
15 ably attachable at each of its sides, yet having
an intervening surface concaved laterally and
vertically with a gradual rise sloping to an angu-
lar point of graceful lines in comparison to the
austere aspect of either of the patented devices
20 aforementioned, the whole comprising a highly
pleasing satisfactory aspect of the room struc-
ture, the complete elimination of the sharp an-
gular corner greatly facilitating sweeping and
dusting requirements.

25 Numerous other objects and material advantages of the device will more fully appear as this specification proceeds and as is set forth in the appended claim.

We attain these objects by the device described
30 in the accompanying drawing, in which:

Figure 1 is a perspective view showing the corner blocking plate in a corner formed by portions of the walls and the floor of a room:

Figure 2 is a section on line 2-2 of Figure 1, and

Figure 3 is a section on line 3-3 of Figure 1. Similar numerals and letters of reference indicate like parts throughout the several views, thus 10 indicates the corner blocking plate proper which embraces a pair of arms 11 having apertures 12 through which nails, screws, or the like N may be placed for holding contact with the conventional base shoes B.

45 The arms 11 are shaped at their extremities to conform to and enrap the rounded surface of the base shoes, but the body of the plate is less severe in its curvature, diminishing from the arms to the central portion 12 of the plate and
50 thereby completely eliminating any shelf-like shape.

The corner blocking plate presents a concave appearance at the forward or base edge 13 which is planar and rests on the floor F.

55 An apex or sharp tip 14 of the plate is posi-

tioned in the corner formed by the junction J of the side walls W.

Side edges 15 of the plate converging from the arms 11 to the apex 14 contact the sidewalls W. The end edging of these arms extend right angularly from the base line.

The upper surface of the plate adjacent the edges is concavely shaped.

The arms 11 may extend so as to overlap the base shoe B as is shown in Figure 1, or the latter may if desired, be cut-away the relative thickness of the plate so that it may contact, yet overlap the base shoe, flush with the surface thereof.

It should be noted that the plate of our invention is curvilinear in cross-section along its major and minor axis. In other words, from tip to its planar base the plate is generally concave but has minor convex areas within its generally concave whole area, and in all events is curvilinear along vertical and horizontal lines throughout. Moreover, the plate has a unique shape in that it is formed with an ogee curve in vertical section along its major vertical axis, that is, along a wide vertical middle or central portion thereof as is plainly shown in Figure 3. These shapes and formations provide easily reached curved surfaces throughout the exposed area of the plate element (usual dust and dirt catching portions), and make for a better conforming, better appearing unit. It is further characterized by having a depth and height substantially equal to one another.

The device readily commends itself for its ready adaptation as an all purpose corner eliminator. It may be produced from materials readily procurable in the open market and at no great cost, metal, wood, compositions and plastic materials readily lend themselves to its manufacture.

In sizes, too, for specific requirements, its production offers no obstacle, location of installation alone being the deciding factor.

As a labor and material saver in the complete elimination of close fitting and/or mitred ends of the base shoe moulding, it has untold advantages. And in affecting the appearance of a room wherein installed, it makes for marked improvement over the squared corners commonly provided and as covered with either of the devices aforementioned patents disclose.

We are aware that slight modifications may from time to time be made in the details of structure illustrated without departing, however, from the scope of the present invention, and as defined in the claims which are appended hereto. Hence, we do not limit our present invention to the exact description of construction disclosed, but what we do claim is:

- 20 A corner blocking plate having a planar base edge from which end edges extend substantially right angular and above which end edges the remainder of the plate has side edges converging to a sharp tip at the top of the major vertical axis of the whole plate, said plate being curvilinear both vertically and horizontally throughout its whole area and being generally concave on its outer surface except for exteriorly convex and interiorly concave moulding engaging portions extending inwardly from said end edges, said moulding engaging portions having openings for fastenings, the converging side edges extending right angularly for contact with right angular members which form the corner in which the plate is adapted to fit.
